[57] CLAIM

The ornamental design for a non slip tile, as shown and
described.

DESCRIPTION

FIG. 1 is a top plan view of a non slip tile showing my new
design, the bottom being plain and unornamented;
FIG. 2 is a side view of FIG. 1, the other sides being the
same as the side shown; and,
FIG. 3 is a partial cross-sectional view taken along line 3—3
of FIG. 1.
